CABINET CONSTRUCTION

Howard E. Blood, Detroit, and Earl F. Hubacker,
Highland Park, Mich., assignors to Borg-
Warner Corporation, Chicago, Ill., a corpora-
tion of Illinois

Application May 27, 1938, Serial No. 210,336

3 Claims. (Cl. 62—116)

This invention relates to cabinet construction.

A principal object of this invention is to provide a new type of cabinet construction made of an inexpensive, light, insulating material, and which is particularly suitable for use in refrigerator construction.

A further object of the invention is to provide a refrigerator cabinet in which the insulated food compartment will be separable from the refrigerating apparatus so as to allow the entire working parts of the refrigerator to be removed as a unit.

Another object of the invention is to provide a refrigerator construction which comprises a framework for supporting the refrigerating apparatus and a heat insulated compartment removably mounted upon the framework and constructed independently thereof.

Another object of the invention is to provide a molded refrigerator cabinet, means for mounting the cabinet and the refrigerating apparatus and a method of molding the cabinet.

Another object of the invention is to provide a refrigerator cabinet which will have a greater thermal efficiency than refrigerator cabinets now in use and yet which is adapted to be manufactured more cheaply than it is now possible to manufacture refrigerator cabinets.

Another object of the invention is to provide a new and less expensive method of constructing a heat insulated cabinet.

Other objects of the invention will be apparent from a consideration of the following specification and the accompanying drawings, of which there are three (3) sheets and in which:

Fig. 1 represents a front view of a refrigerator cabinet embodying our invention;

Fig. 2 is a vertical sectional view from front to rear of the cabinet shown in Fig. 1;

Fig. 3 represents a section taken along the line 3—3 of Fig. 2;

Fig. 4 represents a section taken along the line 4—4 of Fig. 2;

Fig. 5 represents a section taken along the line 5—5 of Fig. 2;

Fig. 6 represents a section taken along the line 6—6 of Fig. 2;

Fig. 7 represents a section taken along the line 7—7 of Fig. 2 with the insulation removed;

Fig. 8 represents an enlarged side view of the evaporator support;

Fig. 9 is a view of an insulating insert to fill the slot in back of the refrigerator through which the liquid and suction lines pass;

Fig. 10 is a vertical sectional view of a refrig-

erator showing a modification of our invention;

Fig. 11 shows a second modification of our invention and represents a vertical sectional view through a refrigerator cabinet;

Fig. 12 represents a section along the line 12—12 of Fig. 11;

Fig. 13 is a third modification of our invention and represents a front view of a refrigerator with the door and machine compartment panel removed; and

Fig. 14 is a section taken along the line 14—14 of Fig. 13.

In Fig. 1 there is illustrated a heat insulated refrigerator cabinet indicated generally at 20 having a provision compartment closed by a door. The cabinet 20 comprises in general heat insulated walls arranged to provide a provision compartment 24, an apparatus compartment 26 and a refrigerating system which includes an evaporator 28 arranged within the provision compartment 24 and a condensing unit indicated generally at 30 arranged within the apparatus compartment 26.

More specifically the refrigerator construction illustrated in Figs. 2 to 9, inclusive, comprises a base unit indicated generally at 32 forming a support for the refrigerating apparatus and for the structure which provides the provision compartment 24. The base unit 32, as illustrated in Fig. 2, comprises a plurality of frame members 34 rigidly secured together so as to provide a box-like frame 35, legs 36 which support the box-like frame above the floor and a pair of standards 38 which are arranged at one side of and which extend above the upper surface of the box-like frame 35. The frame members 34 and the standards 38 may, as illustrated, comprise suitable lengths of angle iron, or the box-like frame 35 may be constructed of wooden frame members if desired.

The refrigerating apparatus may be of any desired type but, as illustrated, comprises a system of the compressor, condenser, expander type which includes a compressor 40 driven by an electric motor 42 through a belt and pulley drive 44, a condenser 46 and receiver 48 and the evaporator 28. The compressor, motor, condenser and receiver may be designated as the condensing unit 30 and be mounted upon a platform 50 which may be suspended by springs 52 from brackets 54 carried by the frame members 34 of the base unit 32. The evaporator 28 may include a liquid and gas header 56 and a sleeve 58, the header 56 being connected by suction and the liquid lines indicated generally at 60 to the

condensing unit and the sleeve 58 having a bracket 62 by means of which the evaporator assembly may be supported by the standards 38. The standards 38 may be connected adjacent their upper extremities by a cross-piece 64 of some insulating material, such as wood, having a plate 66 secured thereto and to which plate a bracket 68 is secured which may consist of a U-shaped metallic member to which the bracket 62 is connected, such as by bolting. The cross-piece 64 may be connected to the standards 38 by bolts and the plate 66 may be held in place upon the cross-piece 64 by means of screws. Also screws may be employed for securing the bracket 68 to the plate 66.

In addition to providing a support for the refrigerating apparatus, the base unit 32 forms a support for the structure which provides the provision compartment 24.

As illustrated in Figs. 2 to 8, inclusive, the provision compartment 24 may be formed by a cube-like shell indicated generally at 70 having an access opening adapted to be closed by a door 72. The shell 70 may be made of any desired moldable material which has properties suitable for this purpose. Such materials must be moisture repellent or non-hydroscopic, preferably heat-insulating and non-sweating, must have a high resistance to abrasion as well as a great impact strength so that they are not readily marred, chipped or dented, must be easy to clean, resistant to the absorption of odors, resistant to organic acids and alkalis, such as are generally found in foods, and should show an ability to take a finish upon its surface or to take colors (particularly white) as a part of its composition.

Materials answering the general requirements set forth above are found in a wide variety of plastics. As particular examples of general classes of plastics, which are not intended to be limiting, urea-formaldehyde compounds containing alpha cellulose fillers have been found to be eminently suitable for the purpose, answering all of the requirements for this use. Vinyl chloride-acetate resins which employ a suitable fibrous filler, have also been found to answer the above requirements. These examples represent merely two materials which have been found to have the necessary qualifications for this purpose but are not to be taken as limiting the invention, since any one of a series of plastic materials would serve the purpose contemplated by the invention.

As illustrated in Figs. 1 to 9, the shell 70 is formed to provide the outer surface at the front, sides and top of the cabinet, the walls of the provision compartment 24, a bottom partition 74 and a skirt 76 around the box-like frame 35 and enclosing the apparatus compartment 26 at the sides and front thereof. The shell 70 may be molded around a rectangular frame 78 which defines the access opening to the provision compartment 24. The walls of the shell 70 may, for example, be approximately one-fourth of an inch thick. The shell 70, it will be noted, provides a space between the walls of the compartment 24 and the outer walls of the refrigerator cabinet, and this space in the shell is open at the back.

Insulating material 78 may be blown or packed into this space between the outer walls and the inner tank or the walls of the provision compartment 24. The partition 74 closes the space between the bottom wall of the provision com-

partment 24 and the top of the apparatus compartment 26. After the insulation has been packed into the space around the inner tank so as to fill the same, a rear rectangular frame member 80 may be inserted around the rear end of the inner tank for closing the space between the inner tank and the outer walls of the cabinet. This frame acts to support the rear end of the inner tank, provides a closure for the space within which the insulation is arranged and also forms a part of the means by which the shell 70 is secured to the base unit 32. After the frame 80 is inserted in the shell, a block of insulating material 82 may be pressed into the back of the refrigerator to complete the insulation and to bring the back of the provision compartment flush with the edges of the shell 70. This block 82 of insulation may comprise a package of insulation wrapped in some waterproof material, such as a waterproof paper, and the edges of the block 82 fit tightly against the inside edges of the shell 70 so as to retard air circulation. A sealing compound indicated at 84, such as asphalt, may be used between the periphery of the block 82 and the opposite surface on the inside of the shell 70 as well as between the inside face of the block 82 and the rear face of the frame 80 and the rear surface of the back wall of the provision compartment 24. In this manner the block 82 of insulation is secured firmly in place and the insulating material 78 is sealed within the space within the shell 70 and between the outer walls thereof and the walls of the inner tank 24. The frames 76 and 80 may be constructed of wood.

The block 82 of insulation is provided with a central opening which coincides with an opening provided in the rear wall of the tank 24 and through which the evaporator 28 is inserted into the provision compartment 24. The standards 38 carry a wall section or portion adapted to close said openings and which comprise a plate 84 and a block of insulating material 86 carried by and fitted around the bracket 68. The plate 84 may be provided with a rolled edge adapted to seal against a gasket 88 carried by the edge 90 of the opening in the rear wall of the provision compartment 24. The block of insulation 86 is formed to fit over the plate 84, the cross-piece 64 and the bracket 68, and the plate 84 which may be formed of the same material as the walls of the shell 70 also is formed to fit over the bracket 68. The edges of the block 86 fit tightly within the opening in the block of insulation 82 and if desired the adjacent surfaces of the blocks of insulation 82 and 86 may be coated with asphalt or some other sealing compound. The frame 80 at the corners thereof may carry four rearwardly extending bolts 92 which extend through the block of insulation 82 and suitable apertures in the standards 38 where the threaded ends thereof are provided with nuts which assist in holding the shell 70 in assembled relationship with the base unit 32.

The upper surface of the box-like frame is adapted to form a seat for the shell 70, the partition 74 thereof resting upon horizontal surfaces provided by a part of the box-like frame 35. To further assist in holding the shell 70 in assembled relationship with the base unit 32, bolts 94 passing through suitable openings in the box-like frame 35 and the partition 74 may be threaded into threaded bushings 96 carried by the bottom portions of the frames 76 and 80 for clamping the frames 76 and 80 and the shell 70 to the base

unit 32. These bolts 94 would have to be inserted after the shell has been seated upon the base unit 32.

The frame 76 provides a support for the hinges upon which the door 72 is hung. The door 72 may include a frame 98 and a filler of insulating material 100 arranged within a molded shell 102 which forms the outer surface of the door. The shell 102 of the door may be formed of the same material as the shell 70 and may be molded around the frame 98 and the insulation 100 so as to seal the insulation therein. An annular gasket 104 which may be carried by the door 72 is adapted to provide an air seal between the door 72 and the front surface of the shell 70 about the door opening so as to prevent the circulation of air into and out of the provision compartment 24 when the door 72 is closed. The bottom of the provision compartment may be provided with a glass, porcelain or metallic plate 106 cemented or otherwise suitably secured to the bottom wall of the compartment 24. The frame 98 of the door 72 and the frame 76 of the shell may have mounted thereon in any suitable way locking mechanism for holding the door in a closed position, and a handle 108 for the door 72 and by which the locking mechanism may be released.

The plate 84 and block of insulation 86 may be provided with a slot 100 adjacent the bottom edge thereof and through which the liquid and suction lines 60 pass, and a block of live rubber 112 may be arranged to fit in the slot 110 and around the liquid and suction lines for sealing the same to the walls of the slot.

The skirt 76 is adapted to close the sides and front of the apparatus compartment and to conceal all of the base unit except the legs 36 thereof.

In practice the shell 70 may be formed by molding the same out of any suitable material, such as one of the materials previously specified, and the outer surface thereof finished as previously indicated. The door 72 may then be assembled to the shell 70 and the insulation 78 and frame 80 arranged within the shell as previously set forth. The refrigerating apparatus may be constructed, assembled and tested and then assembled to the base unit 32, together with the removable wall section 86 and 84. Thereafter the shell 70 may be assembled to the base unit 32 simply by setting the partition 74 upon the upper surface of the box-like frame 35 in such a way that the removable wall section 84 and 86 will enter and close the opening at the back of the provision compartment and also so that the bolts 92 will line up and enter the holes provided therefor in the standards 38. Thereafter the nuts may be applied to the bolts 92 and the bolts 94 may be threaded into the bushings 96 carried by the frame members 76 and 80.

In Fig. 10 there is shown a modified form of the invention wherein the provision compartment 124 is provided by molding a mass of insulating material around a cube-like frame 176 to form a shell 170. In this form of the invention the shell consists of insulating material 178 and a cube-like frame 176 which are molded together to form an integral unit having thick walls. The inner and outer surfaces of this unit are coated with a suitable material to form a skin or coating 179 which is moisture proof, wear resistant and which provides a suitable external surface and an internal finish for the provision compartment. This coating should have the characteristics

previously set forth in connection with the coating specified in connection with the construction illustrated in Fig. 2.

In this modification, the frame 176 may be notched, as illustrated, to provide a better bond between the insulation and the frame. The door 172 may embody the same construction as that utilized in making the shell 170. The construction of this modification may otherwise be the same as that illustrated in Fig. 2 and may be assembled to the base unit 32 in the same manner. As the construction illustrated in Fig. 10 does not provide a covering for the apparatus compartment 126, a separate removable skirt 125 which forms a continuation of the surfaces of the shell 170 may be provided for closing the front and sides of the apparatus compartment.

The modification illustrated in Fig. 11 is similar to that shown in Fig. 10 except that in the construction of Fig. 11 the corner posts 275 of the cube-like frame 276 extend the full height of the refrigerator cabinet and provide a part of the supporting frame work 232 for the condensing unit 230 and the provision compartment 224. The corner posts 275 may be connected adjacent their bottom by frame members for strengthening the assembly.

In this modification, the evaporator 228 is supported by means of a pair of brackets 229 carried thereby and which are bolted or otherwise secured to brackets 231 carried by a part of the frame 276 and partially imbedded in the insulation connecting the members thereof. The walls of the shell 270 which forms the provision compartment 224 may be formed in the same manner as the construction illustrated in Fig. 10.

In this modification the liquid and suction lines 260 pass through a slot 277 formed in one of the vertical corner posts 275 and which slot 30 at one end thereof communicates with the apparatus compartment 226 and at the other end with the provision compartment 224 at the upper corner thereof adjacent the door opening. The slot 277 may be packed with insulation and covered as by means of a plate 279 which may be nailed to the frame work 276 at the edges of the slot 277.

In this modification the sides and front of the apparatus compartment 226 are covered by a removable cover or skirt 225 which may be secured to the corner posts 275 in any suitable manner. Upon removal of the skirt 225 and the plate 279, and when the door 272 is open, the refrigerating apparatus may be removed from the cabinet 30 without disassembling any part of the system. The mounting of the condensing unit 230 may be the same as the mounting for the condensing unit in the modification illustrated in Fig. 2. The door 272 may be constructed in the same manner and of the same material as the door 172 in the modification illustrated in Fig. 10.

In Fig. 13 there is disclosed a modified form of the invention embracing a cabinet construction 370 like that disclosed in Figs. 11 and 12, except for the mounting of the evaporator 328 and the manner in which the liquid and suction lines 360 are brought into the provision compartment 324. In Fig. 13 the evaporator 328 is suspended from one end of a horizontal arm 329, the other end of which is fixed to the upper end of a vertical standard 331 pivotally mounted in a bracket 333 affixed to a bottom horizontal frame member of the base unit 332. The standard 331 extends through a slot 377 formed

in the horizontal wall between the apparatus compartment 326 and the provision compartment 324. The slot 317 is formed in a part of the frame 376 of the cabinet and is covered by a removable plate 379 held in place by means of screws 381. A suitable packing may be arranged in the slot below the plate 379 and around the standard 331 for sealing the provision compartment 224 against circulation of air thereinto. The standard 331 may be grooved, as illustrated, to accommodate the liquid and suction lines indicated at 360. The walls of the slot 317 and the cover plate 379 may be formed so as to provide an upper bearing for the standard 331 so that the evaporator may be swung into and out of the provision compartment 324. The liquid and suction lines 360 should be sufficiently flexible and arranged so as to permit the turning of the standard 331 through an arc of at least 90 degrees without injuring such lines. The front and sides of the apparatus compartment 326 would be closed by a removable skirt, such as the skirt 225 in Fig. 11, and which skirt forms a continuation of the front and side walls of the provision compartment.

While the invention has been described with some detail, it is to be understood that the description is for the purpose of illustration only and is not definitive of the limits of the inventive idea. The right is reserved to make such changes in the details of construction and arrangement of parts as will fall within the purview of the attached claims.

We claim:

1. A rectangular frame defining a door opening, a fibrous casing molded around said frame and defining a refrigerator cabinet, a fibrous food tank internally spaced from said cabinet

and integrally molded with said casing at said door opening, insulating material packed around said tank, a frame for supporting said cabinet and adapted to receive compressing machinery, a standard rising above said frame and adapted to support an evaporator forwardly thereof, an opening in the back of said tank for inserting an evaporator therethrough and insulating means carried by said standard.

2. A box-like frame one side of which defines a door opening, insulating material molded around said frame to form a cabinet and a compartment therein, a layer of pigmented finishing material covering said frame and molded insulation inside and out, means for supporting said cabinet, an evaporator for cooling said compartment, evaporator supporting means on said cabinet supporting means, an opening in the rear of said cabinet for inserting said evaporator into said compartment and compressing machinery carried on said cabinet supporting means.

3. A refrigerating compartment with a door opening composed of a frame molded in insulating material for forming the walls thereof, a metal plate in the bottom of said compartment, a continuous pigmented finish molded around said compartment both inside and outside, a door for closing said opening comprising a rectangular frame molded in insulating material and covered with a continuous pigmented finish, a hole in the back of said compartment and means for supporting an evaporator in said compartment through said hole, said supporting means being associated with a frame for supporting compressing machinery and said refrigerating cabinet.

HOWARD E. BLOOD.
EARL F. HUBACKER.
